UNITED STATES PATENT OFFICE.

ANDREW H. BAGGS, OF WHEELING, WEST VIRGINIA.

DESIGN FOR ORNAMENTATION OF GLASS-WARE.

Specification forming part of Design No. 6,002, dated July 23, 1872.

To all whom it may concern:

Be it known that I, ANDREW H. BAGGS, of Wheeling, in the county of Ohio and State of West Virginia, have invented and produced a new and original Design for the Ornamentation of Glass-Ware.

My design consists in the application to glass-ware of a sinuous line, A, representing a cord, from which depend tassels B, attached to the upper curves, short cord-sections or curves, C, being interposed between the main cord and tassels, as shown.

The cord-and-tassel design I intend to apply to a full line of glass-ware, embracing articles of different forms and sizes; and al-

though I prefer to apply the design to the outside of such articles, yet I do not limit myself to the particular place on the article where the ornamental cord and tassel are applied, but may apply such ornaments to the inside, or at any point that may be preferred.

Having thus described my invention, what I claim is—

The design for the ornamentation of glass-ware, substantially as herein shown and described.

ANDREW H. BAGGS.
